ELECTRIC CIRCUIT BREAKERS

Edward Coleman, Walsall, England, assignor to J. A. Crabtree & Co., Limited, Walsall, Staffordshire, England, a British company

Filed June 3, 1960, Ser. No. 33,827

Claims priority, application Great Britain June 16, 1959
25 Claims. (Cl. 200—106)

This invention relates to so-called miniature or moulded case circuit breakers of the kind in which the contacts are disengaged on short circuit or overload conditions by thermally or magnetically tripped mechanism, and in which the casing comprises a pair of flat members between which the contacts and mechanism are housed, such mechanism being automatically re-set, that is prepared after a tripping operation, to be manually actuated to the "on" position by a handle or dolly.

In order to prevent overheating of the contacts of such circuit breakers it is desirable to provide a high pressure engagement between them while the force required for performing tripping should be relatively low. In known constructions the main spring for imparting the contact force also imposes a pressure on the latch engagement of the trip mechanism. Hence any increase in the force of this spring for increasing the contact pressure, renders it necessary undesirably to increase the energy required for effecting release of such latch. For the purpose of minimising this disadvantage lever means may be introduced between the contact arm and the latch so that the force required for releasing the latter may be reduced.

Such arrangements however involve a reduction in the operating speed of the trip mechanism due to the increased inertia caused by the introduction of the lever means between the latch and the contact arm.

The principal object of the present invention is to avoid the disadvantages referred to and to provide an improved circuit breaker of simple and compact construction which can be economically produced while possessing efficient electrical characteristics.

According to this invention the latch or trip force is independent of the main spring. The latter may act on a contact arm connected to one end of a toggle, the other end of which is actuated by a handle for manually operating the circuit breaker to the "on" and "off" positions. On the occurrence of a short circuit or overload, the toggle is broken by a trip lever which is independent of the main spring and contact arm.

This trip lever may have releasable latching engagement with a catch plate operated by the overload mechanism. Thus the armature of an electromagnet may be adapted for imparting an impact or impacts on the catch plate in order to release the latch and enable the spring-stressed trip lever to break the toggle. The tripping energy of the overload mechanism is requisite only for overcoming the latching force imposed by the spring acting on this lever and is independent of the force of the main spring which may be relatively high in order to ensure an effective contact pressure. The spring force acting on the trip lever may be relatively low however so that the small amount of energy available for overcoming the latching force is adequate for consistent and reliable operation.

The catch plate acts as an intermediate member between the armature and the trip lever for the purpose of releasing the spring-loaded trip lever. Thus the latching force is constant and dependent only on the strength of the trip spring and is independent of the contact pressure, in order to achieve the advantages of an effective contact force while necessitating only a low tripping energy.

According to a further feature of the invention a pair 70 of high reluctance paths are provided in the magnetic circuit of a circuit breaker in which the contacts are dis-

2

engaged on short circuit or overload conditions by magnetically tripped mechanism incorporating a hydraulic time delay and comprising a hermetically sealed tube containing a spring and a plunger operating in a fluid such as silicone. One of the high reluctance paths provides a flux for operating an armature on overload conditions and the other for causing its operation on short circuits as hereinafter described.

The one-piece armature floatably located on the magnet frame is adapted to pivot freely against the action of an adjustable spring so as to impinge on a catch plate for releasing the latched engagement of the latter with the trip lever. The catch plate may be pivotally mounted midway of its length, one end being pressed by a spring into latched engagement at its other end with the pivotally mounted trip lever. The latter may be a three-armed construction, one arm being engageable with a toggle connected between an operating dolly and the contact arm, a second arm having latchable engagement with the catch plate and a third arm pivotally mounted in the casing of the circuit breaker.

In order to enable the invention to be readily understood reference will now be made to the accompanying drawings illustrating by way of example one construction of electromagnetically tripped circuit breaker, for carrying the invention into effect, in which drawings:

FIGURE 1 is a sectional elevation with the parts in the "off" position.

FIGURE 2 is a similar view of the upper part of FIGURE 1 showing the parts in the "on" position.

FIGURE 3 is a section on the line III—III of FIGURE 1.

FIGURES 4 and 5 are side elevations of the flat moulded casing members.

Referring to the drawings a casing comprising a pair of flat mouldings 1, 2, ribbed and recessed for receiving the parts and components between them, has a lever or dolly 3 for operating the switch mechanism. On overload the latter is tripped by an electromagnetic device incorporating a hydraulic time delay and comprising a hermetically sealed non-ferrous tube 4, containing a spring 7 and a ferrous plunger 6 operating in a fluid such as silicone. The tube 4, formed with an integral closed end 4^a, has a short counterbore 4^b at its open end. After introduction of the spring 7 plunger 6, and fluid, a closure disc 8 is seated on the annular flange formed by the counterbore, the tube is peened over, and the opening is flooded with solder 10. The helical compression spring 7 acts on a shoulder 6^a of the plunger so that the parts normally occupy the position shown in FIGURE 1.

The tube 4 is disposed within an insulating sleeve 11 which has a short length of reduced thickness to form an internal shoulder 11^a on which is seated a short ferrous sleeve or magnetic shield 12 encircling the forward end of the tube 4. The insulating sleeve 11 is formed with an annular flange 11^x on which is seated the rectangular member 13 of an L-shaped magnet frame or bracket. This member is apertured to enable it to be passed over the iron sleeve 12 and the other lateral member 13^a of the frame, is provided near the bend of the L with a headed pin 14 on which is loosely pivoted one end of a strip-shaped armature 15, disposed substantially parallel to the arm 13^a. Between this pin 14 and its end the arm 13^a is formed with a hole 13^x of such dimensions as to leave only a narrow width of metal on each side of the hole. The reduction in area on each side of this hole produces high reluctance flux paths.

The rear end of the tube 4 is seated in a shallow circular recess in a small rectangular plate 18 having on one edge a short bent-up lug 18^a constituting a pole piece and between which, and the end of the frame member

13^a is a short air gap 13^b. A gap 15^b is also present between the armature and the end 18^a of the pole piece.

A coil 16, disposed around the insulating sleeve or former 11, has one tail end 16^c connected by brazing or welding to a terminal 16^a extending through an opening in the lower wall of the casing and the other tail 16^c, similarly connected to one end of a short length of flexible braid 16^b, the other end of which is welded to a moving contact arm 17. Shield 12 affords the use of a longer length of coil by which the ampere-turns may be increased without undesirable reduction in the cross-section of the wire. This construction reduces the watt loss to a minimum during normal current.

The armature 15 consists of a rectangular plate bent at one end to seat on the frame member 13^a and formed with an aperture which passes freely over the shank of a pin 14 and is retained by the head of the latter. The other end of the armature is bent and is of reduced width to form a shoulder 15^a against which bears a helical compression adjusting spring 19. The improved arrangement, which can be simply and economically produced, facilitates operation of the armature by virtue of its floating location on the rivet 14 which avoids the employment of a bearing involving friction.

The narrow end of the armature 15 extends freely through a rectangular opening 20^a formed in the bent end of a one-piece catch plate 20 to which is secured, midway of its length, a pin 21 the ends of which enter holes in the casing parts to permit pivoting of the plate. The pin 21 is inserted between small semi-circular formations bent outwardly from the plate.

The catch plate 20 adjacent the rectangular aperture 20^a, is formed with an ear 20^b for latching engagement with the end of one arm 24^a of a three-armed trip lever 24, pivotally mounted on a pin 25 projecting, through a hole in the end of a second arm 24^b, into recesses in the casing parts, and the third arm 24^c is formed as a pair of jaws 24^d, 24^e. The jaw 24^e is adapted for impingement on the centre pin 26 of a toggle, comprising the levers 27, 28, and connected between the moving contact arm 17 and the actuating lever or dolly 3. The three-armed lever 24 is made from a flat pressing which simplifies production and enables its different effective points to be accurately located relatively to one another. A nose 24^f between the arms 24^a, 24^b of the lever 24 locates a compression spring 31, operative between the casing and the lever for urging it to turn in an anti-clockwise direction about its pivot 25. Since this effectively operating lever, which ensures accurate tripping, has no bends, it can be economically made from a flat blank.

The moving contact arm 17 is provided with the contact tip 29 at its upper end, and has a transverse pin 32 extending through a hole at its lower end. The ends of this pin enter short horizontal slots 33 formed in internal bosses 34 on the casing parts. A compression spring 35 seated on the rear wall of the casing part 1 bears on the arm between the pins 32 and 37 and acts as hereinafter described. The moving contact 29 co-operates with a fixed contact 30 which is provided on the end of a bent terminal strip 36, introduced through an opening in the upper end wall of the casing part 1.

The toggle comprising the levers 27, 28, is connected at one end to a point midway of the length of the contact arm 17 and at the other end to the pivotal operating lever or dolly for manually operating the circuit breaker to the "on" and "off" positions.

The forward member 27 of the toggle may consist of a pair of arms joined by a bridge 27^a and the rearward toggle member 28 may similarly comprise a pair of arms joined by a bridge 28^a. One of these arms may be of extended length and formed with a hook shaped end 28^b for abutting against the pin 44 in the extended position of the toggle.

In the normal position the spring 7 urges the plunger

6 to the end of the tube as shown in FIGURE 1. With small overcurrents with which it is desired to effect tripping in a time-delayed manner the current passing through the coil 16 will cause the plunger to be pulled towards the plate 18. Thus flux passes through the plunger 6, the pole piece 18^a and gap 15^b, the armature 15, the magnet frame 13 and the sleeve 12. The armature 15 is attracted to the pole piece and the trip mechanism is actuated.

On short circuit conditions, in which tripping must be effected without time delay, the plunger 6 remains in the position shown in FIGURE 1, and a shortened flux path from the reduced end of the plunger across to the arm in the region of the hole, the armature and the bracket, causes attraction of the armature to produce actuation of the trip mechanism. Thus even though the flux in the air gap 13^b between the arm 13^a and the pole piece 18^a and the air gap 15^b between the latter and the armature may be undesirably neutralised by an external field, the attraction of the armature is still ensured. This is due to the concentration of flux through the high reluctance paths in the arm 13^a leaking into the armature and producing an effective pull between the bracket and the armature.

When the armature 15 is attracted it impinges on the bent end of the catch plate 20 to cause the latter to be turned anti-clockwise about its pivot pin 21 against the action of a short helical compression spring 22 seated in a recessed wall 23 of the casing. As a result the ear 20^b is removed from its latched engagement with the trip lever 24 which can thereupon be turned anti-clockwise by its spring 31 to cause the jaw 24^e to strike the pin 26 for collapsing the toggle. The main spring 35 is then able to force the contact arm 17 forwards so that the pin 32 moves to the closed ends of the slots 33, and the arm pivots in a clockwise direction around this pin as a pivot, to disengage the contacts and bring the parts into the position shown in FIGURE 1.

At the same time automatic resetting is effected, the toggle arms being extended and the dolly being moved to the "off" position with the assistance of the two-armed spring 50 having its centre loop coiled around the forward pin 44 of the toggle, with one arm bearing on the centre pin 26 and the other arm of the boss 3^b of the dolly. During this movement the energy of the main spring 35 causes the rear pin 37 of the toggle to be pressed against the jaw 24^d of the trip lever to cause it to turn clockwise in order to stress its spring 31 so that it will be restored to latching engagement with the catch plate 20 when the dolly is operated to the "on" position. The catch plate is restored in readiness for such re-engagement by its spring 22.

When the parts have been moved to the "on" position, and the contacts are pressed into engagement the main spring 35 is enabled to turn the contact arm about the rear pin of the toggle so that the locating pin 32 moves to the forward end of the slots 33.

It will be noted that the latch force, that is the force which is effective for the latching engagement of the trip lever 24 with the catch plate 20, is dependent only on the spring 31, and is quite independent of the main spring 35. Hence the strength of the latter may be substantial for ensuring adequate contact pressure, while the strength of the spring 31 may be relatively weak so that only a small tripping force is required for releasing the latch engagement. The catch plate releases the lever which is loaded by the spring 31, this lever being operated independently of the main spring and the toggle.

The improved catch plate ensures that the tripping mechanism is proof against inadvertent operation due to vibration. The armature construction, provides a small gap with a low magnetic reluctance and the entry of its narrowed end into the enlarged aperture 20^a in the catch plate, permits a limited freedom of movement which provides an impact or series of impacts, which result in

a highly effective tripping action. For, even with a relatively small overload, a series of rapid vibrational impacts may be imparted to the catch plate 20 by the armature 15, to result in the release of the trip lever, while with a greater overload the initial impact may be adequate. The improvements also enable the succession of impacts to be readily effective as the production of the catch plate 20 in brass avoids the possibility of corrosion at the latching zone between the ear 20^b and the lever 24.

The compression spring 19 acting on the armature 15 may be adjusted in order to vary the tripping force. This adjustment may be effected by a screw 38 disposed in a threaded opening in the lower end of the casing. After this factory adjustment has been performed, a rivet for connecting the casing parts may be introduced through aligning holes 39 in such parts, this rivet obstructing the tapped opening, so that subsequent unauthorized access to the screw 38 is prevented.

The contact arm 17 is seated at its pivotally mounted end between the bosses 34 of the casing parts and, at its contact end, it is spaced from arcuate barriers 40 on such parts. Thus at its contact-engaging end, the contact arm is free from engagement with the casing parts 1, 2, the arcuate barriers thereby contributing to the efficient electrical characteristics. These barriers also serve to confine the arc and gases to the contact chamber 40^a which may be fitted in known manner with V-shaped plates 41 between which the contacts are engaged and disengaged.

The gases from such chamber pass to a part-cylindrical chamber 42 in which a swirling action is imparted to them before their emission, at relatively low velocity, through rearwardly directed vents 43. The impingement of hot particles and gases on the curved walls of the chamber 42 assists the cooling action thereon before their emission through the vents.

In the "off" position the contact arm 17 abuts against a transverse pin 42^a seated at its end in countersunk holes in bosses 43^a on the internal walls of the casing parts and disposed on the side of the barriers 40 remote from the contact chamber 40^a. These bosses being adapted to form an extended creepage path between the fixed contact and the switch mechanism. The movement of the locating pin 32 of the contact arm 17 in the open-ended slots 33 produces a wiping action of the moving contact 29 on its fixed contact 30.

The dolly 3 has a cylindrical boss 3^a which fits closely into a shaped mouth 1^a of the casing, thereby tending to prevent the emission of gases through such mouth. The boss is formed with axles 3^b entering recesses in such parts and constituting pivot mountings for the dolly. The boss has a rearward extension 3^c to which the toggle is pivotally connected by the pin 44.

The components of the mechanism are individually assembled and trapped in position between the opposed casing members 1, 2, FIGURES 4 and 5, the improved arrangement enabling mechanical fixing means and processes involving physical union such as press operations, brazing and soldering to be dispensed with, so as to facilitate assembly and rendering it economical in cost. The various holes and slots for receiving the pins and other parts are designated in FIGURES 4 and 5 by the suffix "x" to the numerals designating such parts. These holes are countersunk in order to facilitate registration and assembly. The two casing members are secured together by rivets passing through holes 50^x.

The forms of the invention here described and illustrated are presented merely as examples of how the invention may be embodied and applied. Other forms, embodiments and applications of the invention, coming within the proper scope of the appended claims, will, of course, suggest themselves to those skilled in the art.

I claim:

1. An electric circuit breaker comprising a fixed and a movable contact, a main spring for providing contact pres-

sure, magnetically tripped mechanism including a releasable latch, and trip means for disengaging said latch and said contacts upon short circuit and overload, said latch and said trip means being independent of said main spring, a pair of molded flat case members housing said contacts, said spring and said mechanism therebetween, a handle for manually actuating said mechanism to its "on" position and means for automatically resetting said mechanism after such disengagement for such manual actuation.

2. An electric circuit breaker according to claim 1 wherein said latch includes a trip lever, said trip means includes a low pressure spring, and said circuit breaker includes a moving contact arm cooperating with said fixed contact and actuated by said main spring, a toggle connecting said arm with said handle, and an actuating means working independently of said arm upon overload to permit said trip lever to break said toggle and allow said main spring to release said arm from contact-engaging position.

3. An electric circuit breaker according to claim 2 wherein said actuating means includes an armature of said electro magnetic mechanism, a catch plate actuated by said armature, said trip lever having releasable latching engagement with said plate, said armature acting independently of said arm to permit said low-pressure spring to urge said trip lever to break said toggle and disengage said contacts upon overload.

4. An electric circuit breaker according to claim 1 wherein said electro magnetically operated trip mechanism comprises a hermetically sealed tube filled with liquid therein, a plunger and a spring pressing said plunger disposed in said tube, a coil disposed around said plunger, a magnetic shield encircling said tube at one end thereof and an insulating former for said coil, said former having a length of reduced thickness and an internal shoulder for receiving said shield.

5. An electric circuit breaker according to claim 4 having an L-shaped frame, an aperture disposed in a first member of said frame to receive said shield therethrough, an armature floatably mounted on the second member thereof, and wherein said shield comprises a sleeve encircling said tube for a portion of its length at one end thereof.

6. An electric circuit breaker according to claim 3 wherein said trip lever is provided with three arms, a first arm is engageable with said toggle, a second arm has latching engagement with said catch plate and a third arm is pivotally mounted on said case.

7. An electric circuit breaker according to claim 3 wherein said catch plate is provided with an aperture at one end thereof, said armature extends through said aperture and said mechanism causes said armature to vibrate within said aperture and impart a series of impacts on said catch plate.

8. A molded case electric circuit breaker having magnetically tripped mechanism including an hydraulic time delay, said delay comprising a magnet frame, an armature pivotally mounted on said frame, a hermetically sealed tube filled with liquid, a plunger and a spring acting on said plunger disposed in said tube, the magnetic circuit of said mechanism providing a pair of high reluctance paths, a first path providing a flux for operating said armature on overload and a second path providing a flux for operating said armature on short circuit.

9. An electric circuit breaker according to claim 5 wherein the opposite end of said armature to its floatable mounting is resiliently supported by a small spring and having adjustment means for regulating the operative action of said small spring against said armature.

10. An electric circuit breaker according to claim 7 having an L-shaped frame provided with a first and second member thereof, and in which a headed pin is carried by said second member, said armature is freely

floated on said pin and inserted through said catch plate aperture for resilient engagement with said small spring.

11. An electric circuit breaker according to claim 9 wherein said means comprises a recess in one of said members, a shoulder disposed at one end of said recess for seating said small spring therein, a threaded bore extending from one end of said member to said shoulder, a screw for adjusting the compression of said spring threadedly seatable in said bore, a rivet for securing said members together passing through said bore to prevent access to said screw after adjustment thereof, said rivet adapted to retain form-setting material within said bore when applied against said screw to prevent vibrational turning thereof.

12. A molded case electric circuit breaker comprising a fixed and a moving contact, a contact arm, a strong spring for actuating said arm, a manually operable lever, a toggle connecting said arm to said lever, a trip lever, a weak spring engaging said trip lever and means acting independently of said arm to permit said weak spring to urge said trip lever to break said toggle and allow said strong spring to disengage said contacts on short circuit or overload.

13. A molded case electric circuit breaker comprising electric magnetically tripped mechanism, a fixed contact, a spring-actuated moving contact arm cooperative with said fixed contact, a primary spring actuating said arm, a handle, a toggle connecting said arm with said handle, an overload device provided with an armature, a catch plate actuated by said armature, a trip lever having releasable latching engagement with said plate, a secondary spring and means acting on said secondary spring independently of said arm upon overload for urging said lever to break said toggle and enable said primary spring to disengage said arm from said fixed contact.

14. A molded case electric circuit breaker comprising electromagnetically operated trip mechanism having an armature, a fixed contact, a spring-actuated contact arm cooperating with said fixed contact, a primary spring for actuating said arm, a handle, a toggle connecting said arm with said handle, a catch plate actuated by said armature, trip lever, a secondary spring for urging said lever to break said toggle and enable said primary spring to disengage said arm when said armature imparts a series of impacts on said plate on overload.

15. A molded case circuit breaker having electromagnetically operated trip mechanism, comprising a hermetically sealed tube filled with liquid, a spring-pressed plunger disposed in said tube, a first and second sleeve disposed about said tube, a coil encircling said tube for a portion of its length at one end thereof, said first sleeve having a length of reduced thickness and an internal shoulder acting as an insulating former for said coil, and said second sleeve seated on said shoulder acting as a magnetic shield.

16. A molded case electric circuit breaker having electro magnetically operated trip mechanism comprising a hermetically sealed tube filled with liquid, a magnetic shielding sleeve encircling a portion of said tube, a plate for seating one end of said tube therein, a portion of said plate forming a laterally bent pole piece, an L-shaped frame, a first member of said frame being apertured to pass over said sleeve, the second member of said frame extending to a point proximate said pole piece, and an armature floatably supported on said second member.

17. A molded case electric circuit breaker comprising electromagnetically operated trip means including a liquid filled tube, a spring-pressed plunger slidable in said tube, a coil disposed around said plunger, a floatably mounted armature disposed laterally of said tube, a catch plate actuated by said armature, a trip lever having releasable latching engagement with said catch plate, fixed and moving contacts, a main spring provided pressure engagement between said contacts, means for disengaging said

contacts, and an independent spring for urging said lever to operate said means.

18. A molded case circuit breaker comprising a fixed contact, a moving contact member, a main spring for actuating said member, a handle, a toggle connecting said handle to said member, an overload device, a catch plate actuated by said device, a three-armed trip lever, a first lever arm being engageable with said toggle, a second arm having latching engagement with said catch plate and a third arm being pivotally mounted on said case, and a trip spring for actuating said lever to break said toggle when said plate is actuated to release such engagement, said trip spring being independent of said main spring.

19. A molded case electric circuit breaker comprising magnetically tripped mechanism, a hydraulic time delay, a hermetically sealed tube filled with liquid, a spring and a plunger disposed in said tube, a pole piece forming a plate, a short sleeve, one end of said tube being seated in said plate and the other end in said sleeve, an L-shaped frame, a longitudinal arm of said frame provided with an aperture therein for encompassing said sleeve, a lateral arm of said frame extending to a point proximate said pole piece, an armature floatably mounted on said lateral arm, the circuit through said mechanism providing a pair of high reluctance paths, one of said paths operating said armature on overload and the other of said paths operating said armature on short circuit.

20. A circuit breaker according to claim 19 wherein said armature is a flat metal strip loosely pivoted to said lateral arm and said lateral arm is provided with an opening therein to provide two narrow cross sectional areas producing flux paths of high reluctance either side thereof.

21. A molded case electric circuit breaker comprising an electromagnetically operated trip mechanism including a magnet frame, an adjusting spring, an armature floatably mounted on said frame and operable against the action of said spring, a main spring, a moving contact arm actuated by said main spring, a handle, a toggle connecting said arm to said handle, a trip lever, a catch plate provided with an opening therein pivotally mounted between its ends, a third spring operative adjacent one end of said plate for pressing the other end thereof into latching engagement with said lever, said armature extending freely into said opening for imparting vibrational impacts on said plate, and a fourth spring for urging said lever to impinge on said toggle when such engagement is released.

22. A molded case electric circuit breaker comprising a fixed contact, a moving contact, a trip lever, a plate for latched engagement with said lever, magnetically operated trip mechanism for releasing such engagement, means for automatically resetting said breaker after such tripped release, a relatively strong spring to effect pressure engagement of said contacts and an independent lighter spring to effect such releasable latched engagement.

23. A molded case circuit breaker having electromagnetically operated trip mechanism, said mechanism comprising a hermetically sealed tube filled with liquid therein, a spring-pressed plunger disposed in said tube, a magnetic sleeve encircling said tube for a portion of its length, a wire coiled around said plunger, said sleeve affording increased length and number of ampere turns of said coil without reduction of the cross-section of said wire to effect minimum watt loss at normal current.

24. A molded case circuit breaker comprising a fixed and a moving contact, magnetically tripped mechanism provided with a floatably mounted armature for disengaging said contacts, resilient means for supporting the free end of said armature, adjustment means to vary the compression of said resilient means, access means to said adjustment means after assembly of said circuit breaker in said case, and a catch plate provided with an aperture at one end thereof, the free end of said armature extending through said aperture for engagement with said resilient means.

25. A circuit breaker according to claim 18 wherein a flat blank forms said three-armed lever.
